CLAIM

The ornamental design for a drain strainer, as shown and described.

DESCRIPTION

FIG. 1 is a top perspective view of a drain strainer, showing my new design;

FIG. 2 is a bottom perspective view thereof;

FIG. 3 is a top plan view thereof;

FIG. 4 is a front elevational view thereof;

FIG. 5 is a right side elevational view thereof;

FIG. 6 is a rear elevational view thereof;

FIG. 7 is a left side elevational view thereof;

FIG. 8 is a bottom plan view thereof; and,

FIG. 9 is a sectional view thereof taken along line 9-9 in FIG. 3.

1 Claim, 9 Drawing Sheets
